UNITED STATES PATENT OFFICE.

PATRICK J. MADDEN, OF DEPOSIT, NEW YORK.

RAILROAD-TIE.

1,105,675.

Specification of Letters Patent.

Patented Aug. 4, 1914.

Application filed October 10, 1913. Serial No. 794,513.

To all whom it may concern:

Be it known that I, PATRICK J. MADDEN, a citizen of the United States, residing at Deposit, in the county of Broome and State of New York, have invented certain new and useful Improvements in Railroad-Ties, of which the following is a specification.

My invention relates to an improvement in railroad ties, and it has for its object to construct a railroad tie by utilizing parts of wooden ties already laid to economize in the use of wood for tie purposes, and at the same time to give a rigid and safe support for the rails.

It is well known that there is a great waste in railroad ties. Ties partly used and from which may be cut perfect and sound parts, are thrown away. It is for the purpose of utilizing these parts that my device is constructed so as to form a combined tie and plate, which while preventing the waste of timber, at the same time presents the springing features of wood and the strength of a metal tie and tie plate to effectually prevent the spreading of the rails.

With this object in view, my invention consists in certain novel features of construction and arrangement of parts as will be hereinafter fully described and pointed out in the claims, reference being had to the accompanying drawings, in which—

Figure 1 represents a side view of my device. Fig. 2 represents a plan view of my device. Fig. 3 represents a plan view of a modified form of a part of my device. Fig. 4 represents a side view of a modified form of my device. Fig. 5 represents a side view of a modified form of my device. Fig. 6 represents an end view of a modified form of my device.

The same reference characters denote like parts in each of the several figures of the drawing.

In the carrying out of my invention, I have the wooden blocks or sections of a tie, A. A. Mounted on these I have the plate B, which plate has in it at both ends, the perforations, 2. 2. 2. 2. for the insertion of spikes 3. 3. 3. In the center of the plate B I have the bolt holes 4. 4. In each end of plate B I have the recess 5. 5. From the base of the recess I have the turned up lugs 6. 6', the lug 6 being turned over in hook formation, while the lug 6' projects vertically at right angles to the plate B. Mounted on plate B I have the clamps 7. 7 which

terminate in a threaded neck which projects through the bolt holes 4. 4, and on which are mounted the nuts 8. 8.

In a modified form of the plate B, I have the plate B', the difference being the waist formation making the center of the plate B' narrower than that of plate B.

In a modified form of the clamping members of my device I have the plate C extending under and supporting the lower sides of the blocks A. A, and through which are passed the bolts 9. 9 on which are mounted the nuts 8. 8.

In a modified form of my device I place between the plates B and C, plate D having the opposite edges 10. 10, turned at right angles to the body portion D, which is set vertically between the plates B and plate C, as shown in Figs. 5 and 6. These edges 10/10 are perforated, and through these and through the plates B and C pass the bolts 9. 9.

Having thus described my invention, what I claim as new and for which I desire Letters Patent is as follows:

1. In a railroad tie, opposite supporting members of wood, a plate mounted thereon forming a binding connection between the members, each end of said plate having a recess therein; projecting lugs projecting from the base of each of said recesses and beyond the upper surface of said plate, one lug projecting vertically at right angles, the other in hooked formation, and each adapted to engage the outer edge of the base of a track rail; a lug in L formation projecting under said support mentioned, and removably mounted in said tie plate.

2. In a railroad tie, opposite supporting members, a perforated plate having a central narrow waist formation mounted on the same; a recess in each end of said plate, lugs projecting upward from the base of said recess, one lug projecting vertically, the other obliquely, each adapted to engage the outer edge of the base of a track rail; a lug in L formation positioned at the inner opposite ends of each of said supporting members and projecting under the same and also removably mounted in said tie plate.

3. A railroad tie comprising opposite supporting members, a perforated binder plate connecting the supporting members, said plate having a recess at each end, lugs projecting upwardly from the base of each recess for engagement with the outer edge of

the rail base, and clamping members positioned at the inner opposite ends of each supporting member and extending beneath the supporting members, said clamping members being removably secured to the binder plate.

4. A railroad tie comprising opposite supporting members, a perforated binder plate connecting the supporting members, said 10 plate having a recess at each end, lugs projecting upwardly from the base of each recess for engagement with the outer edge of the rail base, and clamping members dis-

posed between the supporting members and removably secured to the binder plate at the 15 inner opposite ends of each supporting member, said clamping members extending beneath the supporting members for securing the plate and supporting members together.

In testimony whereof I have affixed my signature in presence of two witnesses.

PATRICK J. MADDEN.

Witnesses:

JAMES H. ROBERTS,
M. F. TERRY.
